UNITED STATES PATENT OFFICE.

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 8, 1924. Serial No. 730,928.

To all whom it may concern:

Be it known that I, BERNARD E. O'HAGAN, a citizen of the United States, residing at Swissvale, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing means controlled by energy received from the trackway. More particularly my invention relates to the trackway portion of such apparatus.

I will describe one form and arrangement of railway traffic controlling apparatus embodying my invention, and will then point out the novel features thereof in claims.

The accompanying drawing is a diagrammatic view showing one form of trackway apparatus embodying my invention.

Referring to this drawing, the reference characters 1 and 1^a designate the track rails of a stretch of railway track over which traffic normally moves in the direction of the arrow. These track rails are divided, by means of insulated joints 2, into a plurality of successive track sections A—B, B—C, etc. Each of these sections is provided with a trackway signal designated by the reference character S with a suitable exponent. These signals may be of any suitable form, and since they form no part of the present invention, the circuits for operating these signals have been omitted from the drawing for the sake of simplicity.

Sections A—B is provided with a track relay R' comprising two windings 20 and 21. One winding 20 is constantly supplied with alternating current from some suitable source, such as an alternator M, over line wires 6 and 6^a. The other winding, 21, of this relay is constantly connected across the rails adjacent the entrance end of the section. The track relay may be used to control train governing means, not shown in the drawing, in any desired manner. Section A—B is further provided with a track transformer T' having a secondary 3 constantly connected across the rails adjacent the exit end of the section. An impedance 4 is interposed between secondary 3 of trans-

former T' and one rail, 1, of the associated section in the usual manner, and the primary 5 of transformer T is constantly supplied with alternating current from line wires 6 and 6^a.

The trackway apparatus here shown is suitable for controlling train carried governing apparatus responsive to the presence of alternating current in the track rails, and this control is, in certain systems, effected through the medium of receiving apparatus carried in advance of the forward axle of the train. In such systems, it will be seen that the source of alternating current must be connected across the rails in advance of the train.

In some instances, however, it is desirable to connect the track transformer across the rails at the entrance end of a section. One example of such an instance, is shown in section B—C. This section is "cut" by being divided, by means of insulated joints 2 at point X, into a rear sub section B—X, and a forward sub section X—C, as for the purpose of controlling a highway crossing signal not shown in the drawing but located at the intersection of the railway with a highway Q. Under these conditions a track transformer T² is connected across the rails adjacent the left hand end of sub section B—X, and a similar track transformer T³ is connected across the rails adjacent the right hand end of sub section X—C. These two transformers T² and T³ are constantly supplied with alternating current over line wires 6 and 6^a. Located at point X are two track relays R² and R³ each similar to relay R' and each having a winding 20 constantly connected with line wires 6 and 6^a. The winding 21 of relay R² is connected with the rails adjacent the exit end of sub section B—X, and winding 21 of relay R³ is connected across the rails adjacent the entrance end of sub section X—C. With this arrangement it will be clear that a train progressing through section A—B or sub section X—C in the direction of the arrow will have its governing apparatus supplied through the associated receiving apparatus with alternating current from a transformer T connected across the rails in advance of the train, but that a train moving in this direction through sub section B—X will have the alternating track current shunted

away from the receiving apparatus by the wheels and axles of the train since the source of supply of alternating current for this sub section is located in rear of the train.

5 I therefore provide sub section B—X with an auxiliary transformer H having its secondary 3 connected, through an impedance 4, across the rail adjacent the exit end of sub section B—X. This transformer
 10 is so connected that the current supplied thereby to the rails is of an instantaneous relative polarity opposite to that supplied to the rails by transformer T². Current from this transformer, therefore, will not
 15 pick up relay R², and furthermore, the parts are so proportioned that if sub section B—X is unoccupied and transformers T² and H are both energized, the currents supplied by these two transformers will neutralize each
 20 other in their effect upon relay R². To control the supply of current to transformer H I connect a slow acting relay K across the rails adjacent the point of connection of transformer T². By slow acting I mean
 25 that the relay is so constructed that when the relay is energized a considerable interval of time elapses subsequent to the opening of the back contact and prior to the closing of the front contact thereon. The
 30 circuit for transformer H may be traced from line wire 6, through wire 7, front contact 8 of relay R³, wire 9, back contact 10 of relay R², wire 11, primary 5 of transformer H, wire 12, front point or back point of contact 13 of relay K, and wire 14 to line
 35 wire 6^a.

As shown in the drawing the parts are all in the positions corresponding to the unoccupied condition of the stretch of track shown in the drawing. Under these conditions all track transformer T are energized, all track relays R and slow acting relay K are also energized, but the circuit for transformer H is broken at back contact 10 of relay R². I will now assume that a train, moving in the direction of the arrow passes through the stretch of track shown in the drawing. As this train proceeds through section A—B the governing apparatus on the train receives energy from transformer T' toward which the train is proceeding. As the train enters sub section B—X, relays K and R² become de-energized, thus supplying current to transformer H, which in turn supplies alternating current to the rails of the sub section for the control of the train carried governing apparatus. As the train enters sub section X—C the de-energization of relay R³ interrupts the circuit for transformer H and when the train moves out of sub section B—X, the energization of relay R² restores the apparatus to normal.

I will now assume that a train moves
 65 through the stretch of track shown in the

drawing in a direction opposite to that indicated by the arrow. Relay R³ will then be de-energized as the train enters sub section X—C. When the train enters sub section B—X, relays K and R² become de-energized. When the train clears sub section X—C, the energization of relay R³ completes the circuit for transformer H but, because of its relative polarity, current from this transformer is ineffective to energize relay R², and the circuit therefore remains closed for transformer H at back contact 10 of relay R². When the train clears sub section B—X, relay K picks up. Due to the slow acting characteristics of relay K the circuit for transformer H is opened for a time interval and during this interval the supply of alternating current to the rails by transformer H is discontinued. As a result current from transformer T² picks up relay R² and when the front point of contact 13 finally closes it is not effective to re-energize transformer H because the circuit for this transformer is now open at back contact 10 of relay R². When the train leaves section A—B, the energization of relay R' returns the apparatus to its normal condition.

As here shown my invention is applied to a cut section arranged to control a highway crossing signal but it should be pointed out that the invention may be applied to a track circuit under other conditions in which the track transformer is located at the entrance end of the block and it is desired to control train carried governing apparatus by means of current in the track rails.

Although I have herein shown and described only one form and arrangement of trackway circuits embodying my invention, it is understood that various changes and modifications may be made therein within the scope of the appended claims without departing from the spirit and scope of my invention.

Having thus described my invention, what I claim is:

1. In combination, a stretch of railway track, a first track transformer connected across the rails adjacent one end of the stretch and constantly supplied with alternating current, a second track transformer having a secondary connected across the rails adjacent the other end of the stretch, a track relay connected across the rails of said stretch and arranged to be operated by current from said first transformer but not by current from the second transformer, a slow acting relay also connected across the rails of the stretch, and means controlled by both said relays for at times supplying said second transformer with alternating current.

2. In combination, a stretch of railway

track, a first track transformer connected across the rails adjacent one end of the stretch and constantly supplied with alternating current, a second track transformer having a secondary connected across the rails adjacent the other end of the stretch, a track relay connected across the rails of said stretch and arranged to be operated by current from said first transformer but not by current from the second transformer, a slow acting relay also connected across the rails of the stretch, and means effective when said track relay is de-energized and said slow acting relay is either energized or de-energized for supplying alternating current to said second transformer.

3. In combination, a stretch of railway track, two track transformers one located at each end of the stretch, a track circuit for said stretch including in series the two rails of the stretch and the two secondaries of said transformers, means for constantly supplying one of the transformers with alternating current, a track relay for said stretch arranged to be picked up when the stretch is unoccupied and said one transformer is energized but to be released when the stretch is unoccupied and both said transformers are energized, means including a back contact of said track relay for energizing the remaining transformer when a train moving in one direction enters the stretch, and means effective when such train leaves the stretch to interrupt the circuit for said second transformer for an interval to cause the track relay to open said back contact.

4. In combination, a stretch of railway track, two track transformers one located at each end of the stretch, a track circuit for said stretch including in series the two rails of the stretch and the two secondaries of said transformers, means for constantly supplying one of the transformers with alternating current, a track relay for said stretch arranged to be picked up when the stretch is unoccupied and said one transformer is energized but to be released when the stretch is unoccupied and both said transformers are energized, a slow acting relay connected in parallel with said one transformer, and a circuit for supplying alternating current to the other transformer over a back contact of said track relay and a back contact of said slow acting relay, said circuit also including a front contact of the slow acting

relay in parallel with the back contact thereon.

5. In combination, a stretch of railway track, means for constantly supplying alternating current to the rails at one end of the stretch, a transformer connected with the rails at the other end of the stretch, means including a first circuit controller and a second circuit controller for at times supplying alternating current to said transformer, means responsive to traffic conditions for at times opening said first circuit controller for an interval of time, and means responsive to such opening of the first circuit controller for opening the second circuit controller to thereby prevent energization of the transformer when said first circuit controller again closes.

6. In combination, a stretch of railway track, a track relay for said section, two transformers one adjacent each end of the stretch and each having its secondary connected with the rails in such manner that when both transformers are energized, said track relay is de-energized, means for constantly supplying one said transformer with alternating current, means including a back contact of said track relay for at times supplying alternating current to the other said transformer, and means for at times temporarily interrupting such supply for a brief interval for the purpose of energizing the track relay whereby the circuit for said other transformer is opened at the back contact of such relay.

7. In combination, a stretch of railway track, means for constantly supplying alternating current to the rails adjacent the entrance end of said stretch, a first track relay connected with the rails adjacent the exit end of said stretch, a second track relay responsive to traffic conditions in advance of said section, a transformer having a secondary connected across the rails adjacent the exit end of the stretch, a slow acting relay connected across the rails adjacent the entrance end of the stretch, and means for supplying alternating current to the primary of said transformer when said slow acting relay is energized or is de-energized provided said first track relay is de-energized and said second track relay is energized.

In testimony whereof I affix my signature.

BERNARD E. O'HAGAN.
